Primary Examiner — Marie D. Fast Horse(74) *Attorney, Agent, or Firm* — Henry M. Feiereisen LLC(57) **CLAIM**

The ornamental design for a data processing equipment, as shown and described.

DESCRIPTION

FIG. 1 is a front view of the data processing equipment showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a front, left side and top perspective view thereof. That portion in the drawings shown in broken lines form no part of the claimed design.
